UNITED STATES PATENT OFFICE.

FLORENTINO AVILES, OF COROZAL, BRITISH HONDURAS.

KEY FOR WATER TANKS.

Application filed January 22, 1926. Serial No. 83,064.

- This invention relates generally to devices for locking water tanks and the like, the invention having more particular reference to a novel type of locking device. The invention has for an object the provision of an improved water locking device which may be readily operated, and which will also regulate the flow of water as may be desired.
- For further comprehension of the invention and of the objects and advantages thereof, reference will be had to the following description and accompanying drawing, and to the appended claims in which the various novel features of the invention are more particularly set forth.
- Fig. 1 is a side elevational view of my improved water locking device attached to a water tank.
- Fig. 2 is an end view thereof, partly in section.
- Fig. 3 is an enlarged longitudinal center sectional view.
- Fig. 4 is a sectional view taken on the line 4—4 of Figure 3.
- Fig. 5 is a transverse sectional view showing the shutter.
- Fig. 6 is a sectional view taken on the line 6—6 of Figure 4.
- As here embodied my improved water locking and regulating device comprises briefly a cone shaped hollow member 10, which is attached to the water tank 11 and which has a slightly enlarged cylindrical hollow portion 12 having a suitable end 13, either integral or detachable by means of bolts, screws or similar fasteners. The cylindrical hollow portion 12 is also provided with an outlet 14, preferably located at the bottom thereof, and of circular shape. The cylindrical hollow portion 12 is further provided with an aperture 15, having a member 16 slidably mounted in the grooves 17, as a means of closing and opening the said aperture 15.
- The key, as used in connection with my improved device comprises a body member 18 which is inserted through the aperture 15, after opening the aperture as heretofore explained. The body member 18 consists of an operating rod 19, with a suitable handle depending therefrom, which is connected to the bell crank 20, as at 21, said bell crank being pivoted as at 22, and being also connected to the rod 23, as at 24, there being a pin 25 extending from the rod 23. By means of a downward pull on the handle of the operating rod 19, the pin 25 will engage with the aperture 26 suitably located in the shutter disc 27, rotatably mounted in the shutter body 28, and having an aperture 29, centrally located therein, said shutter disc 27 having a spring 30 attached thereto as a means of holding the shutters 38 in a normally closed position. The said rod 23 is also connected to the lever 30 which is pivoted as at 31, and which is provided with an arm 32, located directly below the regulating rod 33, which is slidably mounted in an aperture in the cylindrical hollow portion 12 having a cap 34, there being a spring 36 disposed in the aperture, so as to normally hold the regulating rod in an upward position, by means of pressure exerted by the said spring against the enlarged portion 35 of the regulating rod 33, which is also provided with a handle or knob 37. The heretofore mentioned construction is such as will permit the operating rod 19, when pulled downward to engage with the shutter disc 27, and also permit the regulating rod 33 to rotate the shutter disc 27.
- The shutters 38 are of ordinary design and shape, and are pivoted to the shutter body 28, as at 39, there being protruding pins 40 located in the said shutter disc so as to engage with apertures 41 suitably located in the shutters 38, so as to pivotally open or close the said shutters, when the said shutter disc is rotated as described. As a means of assuring the contact of the pin 25, I have provided a plurality of springs 42, disposed between the end 13 of the cylindrical hollow portion 12 and the plate 43, said plate and also the shutter member 28, being a slidably fit in the cylindrical hollow portion 12, so that the springs 42 will force the plate and shutter member 28 against the key assuring engagement of the pin 25 when the operating rod 19 is pulled downward, as hereinbefore stated.
- I have also provided a protruding rod 45, suitably attached to the key, and so located as to force the shut off disc 48 upwards, when the said key is inserted, the shut off disc 48 being slidably mounted in the cylindrical hollow portion 12; as a means of allowing the water to flow into the said cylindrical hollow member when the key is inserted therein and springs 49, attached to the shut off disc 48 and to the cylindrical hollow portion 12, as a means of closing the shut off disc 48 when the key is withdrawn.

therefrom, and I have also provided a protruding pin 46, attached to the shut off disc 48, to engage with a suitably located catch or hook 47 attached to the cylindrical hollow portion 12, when the shut off disc is opened by inserting the key, it being understood that the weight of the shut off disc 48 will disengage the above described mechanism when the key is withdrawn from the cylindrical hollow portion.

It will be understood that my improved device may be attached to all classes of water tank, receptacles, and the like, and that the outlet 14 may also be attached to the water supply line or pipe.

It is obvious that I have provided a means of locking water tanks and the like, so that water may not be drawn therefrom, and that I have also provided a means of regulating the flow of water therefrom.

While I have above described the preferred form, construction and arrangement of the several elements employed, it will be understood that the device is, nevertheless, susceptible of considerable modification therein, and I therefore reserve the privilege of resorting to all such changes as may be fairly embodied within the spirit and scope of the invention as claimed.

Having thus described my invention, what I claim as new, and desire to protect by Letters Patent of the United States is as follows:—

1. A locking and regulating device comprising a cone shaped hollow member having a slightly enlarged cylindrical hollow portion having an end, said cylindrical hollow portion provided with an outlet, and also provided with an aperture having a member slidably mounted in grooves, as a means of opening and closing said aperture, a key comprising a body member which is inserted through the said aperture, and a means of engaging a shutter disc thereto, and a means of opening and closing shutters by a regulating rod slidably mounted in said cylindrical hollow portion, and a means of opening a shut off disc.

2. A locking and regulating device comprising a cone shaped hollow member having a slightly enlarged cylindrical hollow portion having an end, said cylindrical hollow portion provided with an outlet, and also provided with an aperture having a member slidably mounted in grooves, as a means of opening and closing said aperture, a key comprising a body member which is inserted through the said aperture, and a means of engaging a shutter disc thereto, and a means of opening and closing shutters by a regulating rod slidably mounted in said cylindrical hollow portion, and a means of opening a shut off disc, the said body member consisting of an operating rod and a handle depending therefrom, said operating rod connect-

ed to a pivoted bell crank connected to a rod, a pin extending from the said rod, whereby by means of a downward pull on the said handle of the said operating rod the said pin will engage with an aperture located in the said shutter disc rotatably mounted in a shutter body having an aperture centrally located therein, the said rod being also connected to a pivoted lever with an arm, located directly below the said regulating rod, said shutters pivoted to the said shutter body, protruding pins located in the said shutter body so as to engage with apertures located in the said shutters, so as to pivotally open or close the said shutters, when the said shutter disc is rotated.

3. A locking and regulating device comprising a cone shaped hollow member having a slightly enlarged cylindrical hollow portion having an end, said cylindrical hollow portion provided with an outlet, and also provided with an aperture having a member slidably mounted in grooves, as a means of opening and closing said aperture, a key comprising a body member which is inserted through the said aperture, and a means of engaging a shutter disc thereto, and a means of opening and closing shutters by a regulating rod slidably mounted in said cylindrical hollow portion, and a means of opening a shut off disc, the said body member consisting of an operating rod and a handle depending therefrom, said operating rod connected to a pivoted bell crank connected to a rod, a pin extending from the said rod, whereby by means of a downward pull on the said handle of the said operating rod the said pin will engage with an aperture located in the said shutter disc rotatably mounted in a shutter body having an aperture centrally located therein, the said rod being also connected to a pivoted lever with an arm located directly below the said regulating rod, said shutters pivoted to the said shutter body, protruding pins located in the said shutter body so as to engage with apertures located in the said shutters, so as to pivotally open or close the said shutters, when the said shutter disc is rotated.

4. A locking and regulating device comprising a cone shaped hollow member having a slightly enlarged cylindrical hollow portion having an end, said cylindrical hollow portion provided with an outlet, and also provided with an aperture having a member slidably mounted in grooves, as a means of opening and closing said aperture, a key comprising a body member which is inserted through the said aperture, and a means of engaging a shutter disc thereto, and a means of opening and closing shutters by a regulating rod slidably mounted in said cylindrical hollow portion, and a means of opening a shut off disc, the said body member consisting of an operating rod and a handle depending therefrom, said operating rod connected to a pivoted bell crank connected to a rod, a pin extending from the said rod, whereby by means of a downward pull on the said handle of the said operating rod the said pin will engage with an aperture located in the said shutter disc rotatably mounted in a shutter body having an aperture centrally located therein, the said rod being also connected to a pivoted lever with an arm located directly below the said regulating rod, said shutters pivoted to the said shutter body, protruding pins located in the said shutter body so as to engage with apertures located in the said shutters, so as to pivotally open or close the said shutters, when the said shutter disc is rotated, a plurality of springs disposed between the said end of the said cylindrical hollow portion and a plate, said plate and said shutter member having a slidably fit in the said cylindrical hollow portion, so that the said springs will force the said plate and said shutter member against the said key.

5. A locking and regulating device comprising a cone shaped hollow member having a slightly enlarged cylindrical hollow portion having an end, said cylindrical hollow portion provided with an outlet, and also provided with an aperture having a member slidably mounted in grooves, as a means of opening and closing said aperture, a key comprising a body member which is inserted

through the said aperture, and a means of engaging a shutter disc thereto, and a means of opening and closing shutters by a regulating rod slidably mounted in said cylindrical hollow portion, and a means of opening a shut off disc, the said body member consisting of an operating rod and a handle depending therefrom, said operating rod connected to a pivoted bell crank connected to a rod, a pin extending from said rod, whereby by means of a downward pull on the said handle of the said operating rod the said pin will engage with an aperture located in the said shutter disc rotatably mounted in a shutter body having an aperture centrally located therein, the said rod being also connected to a pivoted lever with an arm, located directly below the said regulating rod, said shutters pivoted to the said shutter body, protruding pins located in the said shutter body so as to engage with apertures located in the said shutters, so as to pivotally open or close the said shutters, when the said shutter disc is rotated, a protruding pin attached to a shut off disc so located as to engage with a hook, attached to the said cylindrical hollow portion, when the said key is inserted, the said shut off disc slidably mounted in the said cylindrical hollow portion, as a means of allowing water to flow into the said cylindrical hollow member when the key is inserted therein, and springs attached thereto and to the said cylindrical hollow member as a means of closing the said shut off disc when the key is withdrawn therefrom.

In testimony whereof I have affixed my signature.

FLORENTINO AVILES.
